[57] CLAIM

The ornamental design for a cauldron-shaped votive candle holder, as shown and described.

DESCRIPTION

FIG. 1 is a perspective view of one embodiment of a

cauldron-shaped votive candle holder of the present invention, showing a hanging stand in broken lines for purposes of illustration only and forming no part of the claimed design;

FIG. 2 is a front elevational view of a cauldron-shaped votive candle holder;

FIG. 3 is a rear elevational view of a cauldron-shaped votive candle holder;

FIG. 4 is a side elevational view of a cauldron-shaped votive candle holder;

FIG. 5 is an opposite side elevational view of a cauldron-shaped votive candle holder;

FIG. 6 is a top plan view of a cauldron-shape votive candle holder;

FIG. 7 is a bottom plan view of a cauldron-shaped votive candle holder;

FIG. 8 is a perspective view of an alternate embodiment of a cauldron-shaped votive candle holder of the present invention, showing a hanging stand and a decorative detail in broken lines for purposes of illustration only and forming no part of the claimed design;

FIG. 9 is a front elevational view of FIG. 8;

FIG. 10 is a rear elevational view of FIG. 8;

FIG. 11 is a side elevational view of FIG. 8;

FIG. 12 is an opposite side elevational view of FIG. 8;

FIG. 13 is a top plan view of FIG 8;

FIG. 14 is a bottom plan view of FIG. 8;

FIG. 15 is a perspective view of an alternate embodiment of a cauldron-shaped votive candle holder of the present invention, showing a hanging stand in broken lines for purposes of illustration only and forming no part of the claimed design;

FIG. 16 is a front elevational view of FIG 15.

FIG. 17 is a rear elevational view of FIG. 15;

FIG. 18 is a side elevational view of FIG. 15;

FIG. 19 is an opposite side elevational view of FIG. 15;

FIG. 20 is a top plan view of FIG. 15; and,

FIG. 21 is a bottom plan view of FIG. 15.
